UNITED STATES PATENT OFFICE

1,986,890

RADIO APPARATUS

Edward G. Gage, Brooklyn, N. Y., assignor of
one-half to Lloyd Q. Slocumb, Ferguson, Mo.,
and one-half to Radio Corporation of America,
a corporation of Delaware

Original application May 12, 1922, Serial No.
560,298, now Patent No. 1,708,538, dated April
9, 1929. Divided and this application January
21, 1929, Serial No. 334,088

15 Claims. (Cl. 250—40)

The present application is a division of my prior United States application, Serial No. 560,298, filed May 12, 1922, Patent No. 1,708,538 granted April 9, 1929.

5 This invention relates to the relative construction and adjustment of the coils for inductively relating different circuits or different parts of the same circuit, and means for varying the oscillation period of a circuit. The invention is especially useful in connection with radio telephone and telegraph systems but may have other applications.

10 As is well known devices are employed for inductively connecting different portions of radio apparatus, such devices comprising one coil commonly designated as the primary and a second coil commonly designated as the secondary and these coils are so relatively movable that they can be brought into such desired relationship that the "coupling" may be made as "loose" or "close" as desired. It is also usual to provide means for varying the oscillation period of the circuit such as by varying the capacity or inductance, or both. Such devices are usually mounted upon a board, 15 and it is the main object of the present invention to so combine such coil structures with the panel board on which it is mounted and with the adjusting means for the oscillation period that desired adjustments may be effected as quickly and 20 conveniently as possible.

25 The above object may be attained by providing an improved coil structure and mounting, thus one of the coils may be pivotally mounted and upon the pivotally mounted section is also mounted 30 means for tuning i. e. varying the oscillation period as by varying the number of turns of the coil or a condenser or other suitable means. This may be conveniently accomplished by pivotally mounting one section of the panel board, mounting 35 one of the coils thereon and also mounting thereon the tuning means.

40 The handle for the tuning means may also be used to turn the coil on its pivot to vary the "coupling" whereby convenience and speed in operation is attained. Furthermore the pivotal mounting permits any desired adjustment of the coupling without causing undue projection of the parts from the face of the panel at any time so that the apparatus is compact.

45 50 Other and ancillary objects of the invention will appear hereinafter.

In the accompanying drawings which illustrate the invention:

55 Fig. 1 is a perspective view of a cabinet for a radio telephone receiver set, the front of which

constitutes a panel whereon apparatus according to the present invention is mounted, certain parts of the set being omitted for the sake of clearness;

Fig. 2 is a top plan view, on an enlarged scale, of the apparatus of Fig. 1 with the top cover of the cabinet removed and partly broken away;

Fig. 3 is an elevation looking from the left of Fig. 2;

Fig. 4 is an elevation looking from the right of Fig. 2;

Fig. 5 is a front elevation of a portion of the panel;

Fig. 6 is a diagram of electrical connections showing the manner of connecting the improved apparatus in a radio circuit; and

Fig. 7 is a view similar to Fig. 2 showing a modified form of period varying means.

Fig. 8 is a diagram of electrical connections showing the manner of connecting the modification shown in Fig. 7 in a circuit of the type shown in Fig. 6.

Referring to the drawings, and first to Figs. 1 to 6 inclusive, the radio receiving set therein shown comprises a cabinet having its front formed by the panel board 1 while apparatus on the back of the panel board is enclosed in a housing 2. Certain of the usual parts of a set of this character are omitted from the drawings as they do not aid in illustrating the present invention, and on the other hand would complicate it. Upon the back of the panel board 1 which is made of wood fiber or other suitable material is mounted the primary coil 3 by means of a bracket 4 of any suitable construction. The coil 3 is stationary but the number of effective turns in the coil may be varied by taps 5 from different points in the coil which taps are respectively connected with the contact buttons or point 6 respectively adapted to engage with one end of the metal contact arm 7, the other end of this arm connecting with the contact segment 8 to which a suitable circuit connection is made, an example of which will be hereinafter referred to.

30 35 40 45 50 55 It will be apparent that the number of turns of the coil 3 included in the circuit will depend upon the position of the arm 7 and that these turns may be increased or diminished by turning the arm in one direction or the other by means of a suitable insulating handle 9.

To provide suitable insulating mounting for the switch mechanism comprising the contacts 6 and 8 a disk 10 of bakelite may be inserted in the panel.

The secondary coil 11 of the coupling is in inductive relation to the coil 3 and is mounted upon Fig. 1 is a perspective view of a cabinet for a radio telephone receiver set, the front of which

a bracket 12 adapted to swing on pivots 13 and 14 on the panel board. The coil 11 can swing back and forth on its pivots telescoping with the coil 3 and the "coupling" may be as "loose" or as 5 "close" as desired. A spring 15 interposed between the bracket 12 and a pin 16 in the extended end of the pivot at 14 causes a frictional action or brake upon the bracket so that the coil will not accidentally be dislodged from any 10 position to which it may be adjusted.

Secured to the bracket 12 is another bakelite disk 17 mounted in a correspondingly shaped opening in the panel board but having sufficient clearance so that it may not interfere with the 15 movement of the pivoted structure as referred to. Mounted upon the bakelite disk 17 is a segmental contact 18 engaging one end of the contact arm 19, the other end of that arm successively engaging with the contacts 20 as the arm 19 is turned in one direction or the other by means of the insulating handle 21. The contacts 20 are 20 respectively connected by means of taps 22 with suitable separated points of the coil 11.

It will now be seen that the handle 21 can be 25 grasped and the pivoted structure turned in one direction or the other so as to more intimately or remotely associate the coils 3 and 11 and thereby make the coupling as "loose" or as "close" as may be desired. Also this same handle may be 30 employed to vary the number of turns of the coil 11 which are in circuit and so tune the circuit to the desired period. By providing a common handle for thus varying the coupling and for tuning the apparatus, convenience and speed of 35 adjustment are very greatly enhanced. Furthermore, with the structure shown, it will be seen that the movable structure comprising the adjustable coil 11 does not move perpendicular to the panel so that the operating handle is 40 always easily accessible from the front of the panel.

This is of advantage as compared with, for instance, an arrangement whereby the movable coil is moved in a path perpendicular to the 45 panel to adjust the coupling because, in the last mentioned case, the handle is liable to be pushed so far in as not to be accessible or moved so far out as to form an awkward and easily damaged projection. In the structure of the drawings 50 the adjustable coil 11, it will be observed, has a motion which has a component horizontal to the panel.

It is also to be observed that tuning may be 55 accomplished by variation of the turns of the coil 3 in circuit by turning the handle 9 as before referred to.

Referring now to Fig. 6 it will be seen that the aerial 23 is connected with the segment 8 whence connection is made by the contact arm 7 with 60 one of the contacts 6 and thence through the coil 3 to the ground at 24, the number of turns of the coil 3 included between the aerial and ground depending upon the position of the arm 7.

The coil 11, as before stated, has taps connected 65 respectively with the contacts 20, the coil 11 being connected in any suitable secondary or closed oscillation circuit by means of leads 24 and 25, one of which is connected with the contact segment 18 and the other with one of the 70 end of the coil 11. It will be apparent that tuning of the oscillation circuit may be accomplished by including a greater or less number of turns of the coil 11 in circuit in a manner as before described. The oscillation circuit here shown including the conductors 24 and 25 is the "input" 75

circuit of a vacuum tube wherein the circuit is completed across the intervening space from the filament to the grid.

Referring now to Fig. 7, the tuning of the oscillation circuit is effected by the variable condenser 26, which may be of any suitable or well known construction connected in series in the circuit and the movable member of which may be turned by means of a handle 21' mounted upon the bakelite disk 17' which in turn is mounted 10 upon the pivoted bracket 12' carrying the secondary coil 11' in a manner as described in connection with Figs. 1 to 6 inclusive. It will be seen that in this case the pivoted member comprises the panel section 17', condenser 26 and 15 the secondary coil 11' and as its pivoted member is swung the coil 11' is brought into more or less intimate relation with the primary coil 3' which may be mounted and adjusted as described in connection with Figs. 1 to 6 inclusive. 20

In Fig. 8, there is shown in diagrammatic fashion the manner of connecting the modification of Fig. 7 in a circuit. The elements in Fig. 8 which are similar to those shown in Fig. 6 are similarly designated. Thus, as in Fig. 6, the coils 25 3 and 11 are shown as variably coupled by an arrow between them. The coil 3 is represented as variable by an arrow through it, this simple and well known representative being adapted instead of that shown in Fig. 6. As stated above, 30 the variable condenser 26 effects tuning of the oscillation circuit including the coil 11', the condenser being connected in series in the circuit. By means of the leads 24, 25 the coil 11' and condenser 26, both comprising the oscillation input 35 circuit of the tube, are connected between the grid and cathode of the tube, the output circuit of the latter being connected to the output circuit, which, as shown in Fig. 6, includes the head phones. By means of the handle 21', mechanically associated with the movable member of condenser 26 and the coil bracket 12', there is provided a common means for varying the coupling between the antenna circuit, or source of signal 40 energy, and the tuned input circuit of the tube 45 and for tuning the said input circuit, convenience and speed of adjustment being very greatly enhanced thereby. 45

While the invention has been illustrated in what are considered its best applications it may have 50 other embodiments without departing from its spirit and is not therefore limited to the structures shown in the drawings.

What I claim is:

1. The combination with a coil, of a second coil in inductive relation thereto and movable with relation thereto to vary the coupling between said coils, means for varying the oscillation period of a circuit comprising a variable condenser, said period varying means and said second coil being secured together in a unitary structure movable with relation to said first mentioned coil. 55
2. The combination with a panel board having a movable section, of a coil mounted on said panel board, a second coil in inductive relation thereto and movable with relation thereto to vary the coupling between said coils and means for varying the oscillation period of a circuit comprising a variable condenser, said period varying means, said movable panel board section and said second coil being secured together in a unitary structure movable with relation to said first mentioned coil. 60
3. The combination with a coil, of a second 70 coil in inductive relation thereto and movable with relation thereto to vary the coupling between said coils, means for varying the oscillation period of a circuit comprising a variable condenser, said period varying means, said movable panel board section and said second coil being secured together in a unitary structure movable with relation to said first mentioned coil. 75

coil in inductive relation thereto and movable with relation thereto to vary the coupling between said coils, means for varying the oscillation period of a circuit comprising a variable condenser, said period varying means and said second coil being secured together in a unitary structure movable with relation to said first mentioned coil.

4. The combination with a panel board having a movable section, of a coil mounted on said panel board, a second coil in inductive relation thereto and movable with relation thereto to vary the coupling between said coils and means for varying the oscillation period of a circuit comprising a variable condenser, said period varying means, said movable panel board section and said second coil being secured together in a unitary structure movable with relation to said first mentioned coil.

5. The combination with a coil, of a second coil in inductive relation thereto and movable with relation thereto to vary the coupling between said coils, means for varying the oscillation period of a circuit comprising a variable condenser, said period varying means and said second coil being secured together in a unitary structure, said structure being adjustably mounted with respect to said first mentioned coil, and said period varying means being rotatably mounted upon said structure.

6. The combination with a coil, of a second coil in inductive relation thereto and movable with relation thereto to vary the coupling between said coils, means for varying the oscillation period of a circuit comprising a variable condenser, said period varying means and said second coil being secured together in a unitary structure, said structure being adjustably mounted with respect to said first mentioned coil, and said period varying means being rotatably mounted upon said structure.

7. The combination with a panel board having a movable section, of a coil mounted on said panel board, a second coil in inductive relation thereto and movable with relation thereto to vary the coupling between said coils and means for varying the oscillation period of a circuit comprising a variable condenser, said period varying means, said movable panel board section and said second coil being secured together in a unitary structure, said structure being adjustably mounted with respect to said first mentioned coil, and said period varying means being rotatably mounted upon said structure.

8. The combination with a panel board having a movable section, of a coil mounted on said panel board, a second coil in inductive relation thereto and movable with relation thereto to vary the coupling between said coils and means for varying the oscillation period of a circuit comprising a variable condenser, said period varying means, said movable panel board section and said second coil being secured together in a unitary structure, said structure being adjustably mounted with respect to said first mentioned coil, and said period varying means being rotatably mounted upon said structure.

9. In combination, in a radio receiver, a source of signal energy, an electron discharge tube provided with an input and output circuit and includ-

ing a grid, cathode and anode, said input circuit being connected to said grid and cathode, means for coupling said source to said tube input circuit, said means comprising a transformer having a primary winding connected to said source and a secondary winding in said input circuit, a variable condenser connected to said secondary winding in the latter circuit, the condenser being connected between said grid and cathode, means for adjusting said condenser to tune the input circuit to a desired signal frequency, and a common controlling member, mechanically associated with one of the windings and said adjusting means, operable to vary either said coupling or said adjusting means, or to vary both together.

10. In combination with a source of signal energy an electron discharge tube having input and output circuits, means for coupling said source to said input circuit comprising a primary coil connected with said source and a secondary coil connected in said input circuit, said coils being in inductive relationship, one thereof being rotatably mounted for adjustment with respect to the other whereby to vary the coupling between said coils, a variable tuning impedance having an adjustable element for varying the oscillation period of said input circuit, said adjustable element being rotatably mounted and a pivotal common support for one of said coils and said variable impedance element.

11. A radio tuner comprising a variable condenser and an adjustable inductance, in combination with a common operating means arranged and connected to adjust the condenser rotatively and to adjust the inductance by displacement of the common operating means.

12. A radio tuner comprising in combination, a shaft adjustable rotatively and displaceable as a whole, a variable condenser adapted and arranged for adjustment by rotation of said shaft and an inductance adapted and arranged for adjustment by displacement of said shaft.

13. A radio tuner adapted to accommodate infinitely fine gradual adjustment of wavelength, said tuner including a condenser device and an inductance device, each of adjustable character, and a shaft mounted for both rotary movement and displacement as a whole whereby adjustment of said devices may be effected simultaneously through a combination of said movements.

14. A radio tuner comprising a variable condenser and an adjustable inductance member appropriately connected electrically, in combination with a common operating shaft mounted to accommodate rotary movement and adapted to be displaced as a whole, means to adjust the condenser rotatively and to adjust the inductance member by displacement of the common operating shaft.

15. A radio tuner comprising a shaft mounted for rotary adjustment and displacement in combination with a variable condenser operably connected to said shaft for adjustment by rotative movement of the latter and an inductance member having a plurality of windings one of which is adjustable by the displacement of said shaft to vary the effect of said member.
